ALLEN A. BOWSER, OF FORT WAYNE, INDIANA, ASSIGNOR TO S. F. BOWSER & COMPANY, INCORPORATED, OF FORT WAYNE, INDIANA, A CORPORATION OF INDIANA.

PUMP-OPERATING MECHANISM.

1,170,734.

Specification of Letters Patent.

Patented Feb. 8, 1916.

Application filed January 17, 1912. Serial No. 671,551.

To all whom it may concern:

Be it known that I, ALLEN A. BOWSER, a citizen of the United States, residing at Fort Wayne, in the county of Allen and State of Indiana, have invented certain new and useful Improvements in Pump-Operating Mechanism, of which the following is a specification.

This invention relates to improvements in pumps of the type known as "measuring pumps" and one of the objects of the invention is to provide an improved pump of this class having means whereby the reciprocating motion of the pump piston will be converted into a rotary motion for moving the indicator, and means whereby the mechanism which controls the stroke of the piston may be readily and quickly adjusted to vary the piston stroke to accommodate liquids of different densities.

A further object is to provide an improved pump of this class which will be simple, durable, cheap and compact in construction, and effective and efficient in operation.

To the attainment of these ends and the accomplishment of other new and useful objects, as will appear, the invention consists in the features of novelty in substantially the construction, combination and arrangement of the several parts hereinafter more fully described and claimed and shown in the accompanying drawings illustrating an example of the invention, and in which—

Figure 1 is a front elevation partly in section of an improved, pump of this class constructed in accordance with the principles of this invention; Fig. 2 is a sectional view on line 2—2, Fig. 1; Fig. 3 is a detail view taken on line 3—3, Fig. 2; Fig. 4 is a detail sectional view taken on line 4—4, Fig. 3; Fig. 5 is a perspective view of a detail; Fig. 6 is a sectional view taken on line 6—6 Fig. 2; and Fig. 7 is a detail view of the operating crank.

Referring more particularly to the drawings and in the present exemplification of this invention, the numeral 20 designates a pump cylinder within which a pump piston having suitable packing is adapted to be reciprocated by means of a piston rod 22

which passes through a suitable bushing 23 and also a guide 24 formed on a portion of the framework 25. The mechanism for imparting a reciprocatory movement to this 55 piston, preferably comprises a driving gear 25 connected with which is a bearing 26, within which bearing is arranged a bearing block 27 held in position in any suitable manner, preferably by means of fastening 60 device 28 for securing split portions of the bearing 26 for clamping the bearing block 27. A rod or link 29 is pivotally connected by one extremity 30 to the piston rod 23, and this extremity of the rod 29 is deflected 65 or bent laterally, as shown in Fig. 2, to enter a bearing 31 which is secured to the piston rod preferably by means of suitable fastening devices 32, and in which bearing the extremity 30 of the rod is loosely pivoted. A 70 fastening device 33 serves to hold the extremity 30 of the rod against displacement with respect to the bearing 31. The other extremity of this rod 29 is also deflected or bent as shown at 34 and this bent portion 75 has a bearing in the bearing block 27 and eccentric with respect thereto. The free extremity of the portion 34 projects beyond the bearing block 27 and is held by means of a fastening device 35, and if desired, a 80 washer 36 may be disposed between the fastening device 35 and the end of the bearing block 27, which latter has engagement with the face of the gear 25 to hold the bearing block 27 against accidental displacement. Thus when the gear 25 is rotated 85 through the medium of a meshing gear 37, which in turn is journaled in a suitable bearing 38 and is operated by means of a crank handle 39 having a pawl and ratchet 90 connection 40 and 41 with the axle of the gear 37, the rod will be reciprocated and this will in turn impart a reciprocatory movement to the piston rod 22 and the piston 21.

The amount of liquid discharged from the 95 pump is indicated upon an indicator designated generally by the reference numeral 42 over which an index or pointer 43 is adapted to be moved. This index has a rotary motion through the medium of a gear 100 44, the axle 45 of which is journaled in suitable bearings formed by guides 46. The

2

gear 44 is preferably located in front of the gear 25 and in proximity thereto so that when it is rotated, it will move the hand or pointer 43 across the dial. The gear 44 receives its motion from the movement of the piston, but inasmuch as the movement of the piston is reciprocatory, and the index or pointer should be given a constant direction of movement, it would be manifest that it is necessary to disconnect the index or pointer from the piston when it is moving in one direction, and to connect it to the piston when the piston is moving in the other direction. That is to say, the gear 44 must be given a constant direction of movement, while the operating mechanism for this gear has a movement in two directions. In order therefore to accomplish this, there is provided a connection between the gear 44 and the piston rod 23 which embodies two oppositely disposed rack members 47-48 between which the gear 44 is arranged, and the gear is of a diameter less than the distance between the racks. These racks are connected as at 49 to form substantially a U-shaped member depending from which connection is an arm 50 which has a loose connection with the piston rod 23, preferably by means of a slot and pin connection 51-52 and which pin is connected with an arm 53^a on the bearing 31. The rack members 47-48 move between the guides 46 and when one of the members is in engagement with the gear 44, the other is out of engagement therewith. The rack members are adapted to be shifted alternately into and out of engagement with the gear 44, so that when the piston rod is moving in one direction, one of the racks will be in engagement with the gear, but when the piston is reversed to move in the opposite direction, the other rack will be moved into engagement with the gear. This alternate engagement of the racks with the gear 44 will impart a constant direction of rotation thereto as well as to the index, so that the latter will not be moved back over the dial 42 during the return movement of the piston. The racks are adapted to be reciprocated with the piston rod through the medium of a connection between the racks and preferably the gear 25. In order to accomplish this, there is provided a bar or rod 53, one end of which is bent as at 54 and passes loosely through a portion of the arm 50 and is held against displacement by means of a fastening device 55. The other extremity of the rod 53 passes through the bearing 55, which has an apertured body portion 56, and the latter is connected with the gear 25 preferably by means of the bearing block 27 through which apertured body portion 56 the bearing block 27 passes, and this block 27 is provided with a head or shoulder portion 57 of a size much larger than the aper-

ture in the member 55 as shown more clearly in Fig. 4, so that said bearing 55 has free movement with respect to the bearing block. The extremity of rod 53 passes through the bearing 55 and is held against displacement by suitable fastening nuts 58 adjustably engaging the extremity of the rod 53 on each side of the bearing 55. Thus when the gear 25 is rotated, a reciprocating movement will also be imparted to the rack members 47-48.

In order to automatically throw one of the rack members 47-48 out of engagement with the gear 44 at the proper time, and to move the other rack into engagement therewith, there is provided another bar or link 59 (see particularly Fig. 6) which is pivotally connected by one end as at 60, to the arm 50, preferably adjacent the pin and slot connection 51-52 of the arm 50 with the bearing 31. The bar 59 extends through a suitable guide 61 through which it freely moves, and an elastic member 62 surrounds the bar on one side of the guide 61 and has engagement with an adjustable nut or collar 63 on the extremity of the bar. Another elastic member 64 surrounds the bar 59 on the opposite side of the guide 61 and these elastic members are of such a length or size, as to permit the bar 59 to move freely through the guide 61, but before the bar reaches the limit of its movement in either direction, the respective elastic members 62-64 will engage with the guide 61, so that a further movement of the bar 59 in the same direction will compress the respective elastic members.

In Fig. 6 of the drawings the rack 48 is shown in engagement with the gear 44 and is held in this position by means of a suitable guide or extension 65 carried by the rack member and which cooperates with a similar guide or extension 66 carried by the guides 46. These two guides 65-66 are of such a length, and are so disposed with respect to each other, that when the piston 21 reaches the limit of its movement in one direction, the extremity of the guides will be adjacent each other. The respective elastic members 62-64 will also be compressed in the manner already set forth, by the time the extremity of these guides are adjacent each other, and a further movement of the rack in the same direction, will cause the extremity of one of the guides to pass beyond the extremity of the other guide to permit the tension created upon the elastic member to rock the arm 50 about its point of pivotal support 54, to shift one of the racks out of engagement with the gear 44 and the other into engagement with the gear 44 and on the opposite side thereof. After this movement of the racks 48, the piston 21 will begin to move in the opposite direction, and this will also move the racks 130

in the opposite direction of its reciprocation, but inasmuch as the rack engages the gear 44 on the side opposite to that on which it engaged the gear during the first movement 5 of the rack the index or pointer 43 will continue to move in the same direction as it was moved by the first rack. During this shifting movement, the guide 65 will assume a position to pass behind the guide 66 10 and this will operate to hold the rack 47 in engagement with the gear 44. When the piston reaches the limit of its movement in that direction, the other end of the guide 65 will pass behind the other end of the guide 15 66, and the other of the elastic members 62-64 which has been compressed by this movement, will operate to again shift the rack 47 out of engagement with the gear 44 and the rack 48 back into engagement there- 20 with. Thus it will be manifest that a constant direction of movement is imparted to the index 43 while a reciprocatory move- 25 ment is imparted to the piston. Heavy or viscous liquids are not pumped as readily as lighter liquids and sometimes the amount pumped by a single stroke varies. Therefore it is necessary to provide some means to vary the length of stroke of the piston.

When it is desired to vary the length of 30 stroke of the piston to correspondingly vary the amount pumped, all that is necessary is to loosen the fastening device 28 (see Fig. 3), which will permit the bearing block 27 to be rotated in its bearing, and inasmuch 35 as the end 34 of the rod 29 is eccentrically connected therewith, a variable degree of motion may be given to the piston. It is not advisable however, to adjust or vary the movement of the index with respect to the 40 piston, and therefore, in order to obviate such an adjustment or variation of movement of the index, when the stroke of the piston is varied as above described, the pin and slot connection 51-52 is provided which 45 compensates for such adjustment and permits the piston to be adjusted without adjusting or varying the movement of the racks. By loosening the nut of fastening device 67, this adjustment may be obtained, 50 and when adjusted, may be tightened again.

The dials 42 are interchangeable and are graduated in accordance with the amount of liquid to be discharged at a predetermined price, that is to say, as illustrated in the 55 present exemplification of the invention, the dial therein shown is graduated for 1 gallon of liquid at 20¢ per gallon, and other dials may be provided, which are interchangeable with this dial, for the same 60 quantity of liquid at a different price per gallon. All of these dials are placed against each other, and are together arranged within the annular member 68 (see Figs. 1 and 2), and are provided with an opening 65 through which the axle 45 of the gear 44

passes. An annular cap member 69 which has a threaded periphery coöoperating with threads on the annular member 68, serves to hold these dials in position. When it is desired to change the dials, all that is necessary 70 is to unscrew the member 69, interchange the dials and then screw the member back into position.

The index or pointer 43 is adapted to be set to the number of gallons desired, and 75 as the crank handle 39 is operated to discharge the liquid, the index moves from its predetermined position back toward the zero. When it is desired to discharge another quantity, the index must be set to the 80 predetermined quantity. In order therefore to permit the index to be thus set, it must be connected with the axle 45 of the gear 44, which moves it in such a manner as to permit it to be readily adjusted. For this 85 purpose a suitable double clutch mechanism operated by a knob 74, is provided.

In order to guide the piston 21, the piston rod 22 projects for some distance to the other side of the piston and this projecting 90 portion moves through a suitable bushing or bearing 78 at the base of the pump cylinder 20 and into a casing 79. The cylinder 20 of the pump receives its supply through an inlet pipe 80 which has connection with a 95 header 81 with which the pump cylinder has connection, and another header 82 is arranged at the other end of the cylinder, and with which the cylinder has connection. These header members are formed with 100 passages controlled by valves which are so arranged that when the piston is moved in one direction, one of the valves will be opened to permit the liquid to flow into the cylinder, and when the piston is moved in the opposite direction, the liquid which has just entered on one side of the piston, will be forced out of the cylinder through a 105 passage 87 having connection with the cylinder 20 on that side of the piston, to flow through the passage 87, and out through the passage 88 to the outlet pipe 89, which is the discharge of the pump. The 110 operation just described, is effected when the piston is moving downwardly. 115

In order to accommodate any excess liquid which might be drawn into the cylinder over the amount which is discharged, there is provided a receptacle 90 (Fig. 1) 120 which has communication preferably with the header 82, and into which the excess liquid will flow. When the liquid flows into this receptacle 90, a cushion will be formed above the liquid by the air which is compressed in the receptacle by the admission 125 of the liquid so that when the pressure created by the piston is relieved from the liquid, the pressure of the air will operate to force the liquid out of the receptacle.

What is claimed as new is:

1. The combination of a frame having oppositely disposed racks with teeth on the inside, a rotatable toothed member between them adapted to engage one or the other, 5 a reciprocable rod to which the frame is connected for movement, and resilient means having only one connection with the frame for moving the frame laterally at each end of its stroke.
- 10 2. The combination with a rotary toothed gear, of racks on each side of the gear connected together so that the gear engages only one of the racks, a reciprocable member with which the racks are movable, an arm connected to the racks, a rod connected to the arm having springs at the ends, and means to engage the springs whereby the racks are moved laterally at the ends of the strokes of the reciprocable member to move 15 one of the racks into and the other rack out of engagement with the toothed member.
- 15 3. The combination with a driving gear, of a pump rod reciprocated thereby, a frame reciprocated by the rod having opposite inside racks, a pinion to engage one of the racks but not both at the same time, a rod having springs thereon at each end connected to said frame, and a guide through 20 which the rod passes adapted to engage one of the springs at each end of the stroke of the frame and to compress the spring whereby the frame will be shifted laterally to engage the pinion alternately with the racks depending upon the direction of 25 movement of the frame.
- 30 4. The combination with a rotary driving member, of a member reciprocated thereby, a frame with opposite inside racks connected to move with the member, a pinion 35 to engage one but not both of the racks at the same time, and a double spring mechanism in connection with the frame to shift the frame laterally only at the ends of the strokes thereof to change the engagement of the racks with the pinion.
- 40 5. The combination with a rotary driving member, of a rod reciprocated thereby, a frame with opposite inside racks adjustably connected to the rod, a pinion to engage one 45 but not both of the racks at the same time, and means in connection with the frame to shift the frame laterally in opposite directions at the opposite end of its stroke.
- 50 6. The combination with a reciprocating 55 element of a member to be rotated in a single direction, means in connection with the reciprocating element to engage the member on opposite sides thereof, and resilient mechanism connected at one point to the said means for moving it laterally in 60 opposite directions at opposite ends of the stroke whereby the rotary member will be driven in a constant direction.
- 65 7. The combination with a rotary driving member, of a reciprocating member driven 70 thereby, a pinion to be rotated in a single direction, a frame moved by the reciprocating member having opposite inside racks, a spring mechanism connected to one point of the frame, and a rod connecting the frame 75 and the driving member whereby the frame is shifted laterally at each end of its stroke to move one of the racks into engagement with the pinion.
- 80 8. The combination with a rotary driving member, of a rod reciprocated thereby, a pinion adapted to be rotated in a single direction, a frame with opposite inside racks to engage the pinion having a pivotal connection with the rod, a spring mechanism 85 connected to the frame on one side of the pivotal connection, and a rod connected to the frame at the other side of the pivotal connection and to the said driving member for pressing the frame yieldingly in opposite directions at opposite ends of its stroke.
- 90 9. The combination with a rotary driving member, of a reciprocable rod having an adjustable connection with the driving member for varying the stroke of the rod, 95 a frame having a slotted pivotal connection with the rod and provided with opposite inside racks, a pinion having a constant direction of rotation adapted to be engaged by one but not both of the racks, a spring mechanism connected with the frame on one side of the pivotal connection, and a rod connected to the frame on the other side of the pivotal connection and adjustably connected to the rotary driving member to oscillate the frame yieldingly in opposite lateral directions at the opposite ends of its stroke whereby the length of stroke of the frame is maintained constant when the length of stroke of the reciprocable rod is 100 varied.
- 100 10. The combination with a reciprocable rod, of a pinion having a constant direction of rotation, means comprising a plurality of racks movable with the rod for driving the pinion in a single direction, spring mechanism connected to the racks and controlled by the movement thereof for alternately rendering the rack elements active and inactive with respect to the pinion, and means 105 for varying the degree of movement of the reciprocating rod while the degree of movement of the said racks remains constant.
11. The combination with a reciprocating member, of a pinion adapted to be rotated in a single direction, means comprising a frame movable with the member having oppositely disposed racks adapted to be shifted laterally to be alternately rendered active and inactive with respect to the pinion, means in connection with the racks for shifting them laterally at the ends of the strokes thereof, a frame for supporting the racks and pinion having a guide substantially equal to half the length of stroke of 120
- 125 130

the rack, and another guide carried by one of the racks and of substantially the same length as the other guide adapted to be moved on opposite sides of the guide on the frame for maintaining the racks in their shifted positions.

5 In testimony whereof I have signed my

name to this specification, in the presence of two subscribing witnesses, on this 15th day of November A. D. 1911.
